ATTORNEYS

UNITED STATES PATENT OFFICE.

ALEXANDER G. SIEGERT, OF CHICAGO, ILLINOIS.

LOOSE-LEAF BINDER.

Application filed August 1, 1921. Serial No. 489,026.

To all whom it may concern:

Be it known that I, ALEXANDER G. SIEGERT, a citizen of the United States, residing at Chicago, in the county of Cook and State 5 of Illinois, have invented new and useful Improvements in Loose-Leaf Binders, of which the following is a specification.

My invention relates to improvements in loose leaf binders, and it consists in the 10 combinations, constructions, and arrangements herein described and claimed.

An object of my invention is to provide a loose leaf binder of the sectional post variety which is adapted to frictionally hold 15 the sheets in the desired position even though the openings in the sheets of paper are larger in diameter than are the diameters of the sectional posts.

A further object of my invention is to 20 provide a device of the character described which has a novel clamping means for holding the sheets in position.

A further object of my invention is to 25 provide a device of the character described which consists of few parts and which is easy to operate.

Other objects and advantages will appear 30 in the following specification, and the novel features of the invention will be particularly pointed out in the appended claims.

My invention is illustrated in the accompanying drawings, forming part of this application, in which—

Figure 1 is a side elevation of the device, 35 Figure 2 is a plan view of a portion of the device,

Figure 3 is a perspective view of a portion of the device, and

Figure 4 is a section along the line 4—4 of 40 Figure 2.

By referring to the drawings, it will be seen that 1 represents the bottom plate, or cover, on which all sheets rest. This bottom plate contains two holes, each hole 45 reamed from the under-side, which receive the stationary posts, 2. These stationary posts are riveted to the bottom plate. The stationary posts receive, by means of a screw thread, the removable post sections 3. These, 50 besides having the usual threads to connect with other sections, have a threaded hole going through their axis for the purpose of receiving the knurled adjustment screw, 8. 6 represents the fixed portion of the top 55 plate, to which the top cover, 15, is attached

by means of a hinge, 14. Top cover, 15, is bent at 9 to insure close contact between said cover and the paper under it. Top plate, 6, is permanently attached to cam-case, 4, by means of screws, 13. Upper plate, 6, contains two holes, slightly larger than the diameter of the posts, into which holes fit, besides the posts, a metal cylinder, 7, which serves as a support, or pressure link, between adjustment knob 8 and top half of 60 cam-wedge, 5. Cam-wedge 5 contains a hole 65 of about the same size as the diameter of the posts.

The cam wedge 5 has a tubular shank 16 which is rotatably disposed in an opening 70 17 in the casing 4. The opening 17 acts as a guide for the wedge 5, and at the same time permits the wedge 5 to be rotated.

In Figure 3 I have shown a perspective view of the casing 4 and it will be noted 75 that the casing has cam teeth 18 integral therewith, these teeth being disposed in an annular ring concentric with the opening 17. The cam 5 has teeth on its under surface which are adapted to ride upon the teeth 18 80 when the cam 5 is rotated. As clearly shown in the drawing, the wings 19 of the wedges 5 extend beyond the casing 4 and provide a means by which the wedges 5 85 may be swung or rotated. The wedges 5 carry the collars or cylinders 7 which bear 90 against the under side of the adjustment screws 8. It will therefore be apparent that if the wings 19 are swung so as to dispose the portions 20 of the wedges parallel with the outer side of the casing 4, the wedges will be forced up against the cylinder 7, and will move the casing 4 downwardly into engagement with the leaves or sheets 21.

From the foregoing description of the 95 various parts of the device, the operation thereof may be readily understood. When it is desired to place a number of sheets 21 in the binder, the adjustment nuts 8 are removed from the sectional posts 3, thus permitting the casing 4 to be lifted from the posts 3. The leaves or sheets 21 may now be placed on the posts 3, and the posts 3 built up so as to extend a slight distance 100 above the top of the sheets. As clearly shown in Figure 4, the posts 3 have a central threaded bore 22 which is adapted to receive the threaded shank of the adjustment screw 8. The casing 4 may now be disposed 105 on the posts 3 and the cylinders 7 disposed in 110

the openings 23 of the plate 6, whereby they will be carried by the wedges 5. The adjustment screws 8 are now disposed on the posts 3 and are rotated so as to cause the under 5 side of the adjustment screws to engage with the tops of the cylinders 7. The wedges 5 may now be rotated by means of the wings 19 so as to dispose the portions 20 of the wedges parallel with the wall of the casing 10. 4. As heretofore stated, this rotation of the wedges 5 will move the casing 4 downwardly into engagement with the leaves 21, whereby the leaves are frictionally held in position. In the ordinary loose leaf binder of the sectional post variety, the leaves 21 are not 15 positively clamped in position. It is obvious that the openings in the leaves 21 have to be slightly larger than the diameter of the posts 3 so as to permit the leaves 21 to be disposed over the posts 3. The leaves 21 are therefore not firmly held in position by the posts 3. In the ordinary binder, a slight play between the sheets is perceptible. With my present device, however, the sheets 25 21 are positively clamped and are held against movement.

The device is simple in construction and the parts can readily be made as metal castings. It consists of the minimum number 30 of parts and provides a novel means by which the sheets 21 are positively gripped.

For example, if the first digit on each line of a third-point sheet represents "business," and the second digit on a line "salesmanship," then the third digits may represent only such items as pertain to "salesmanship." At the right may be seen the thumb-notches of the other second-point sheets, whose numbers are shown by dotted lines.

40 The fourth-point sheets have a double-depth indentation or cut-out section at the right for the purpose of leading to the fifth-point classifications, the numbers of which—shown by dotted lines—may be seen in the 45 column of thumb-notches immediately next to the fourth-point sheet. Supposing the third digit on each line of the fourth-point sheet represents "closing transactions" under the heading of "Salesmanship," then 50 only such items as relate to "closing transactions" may appear on the lines of the fourth-point sheet. The numbers shown at the bottom of the sheet by dotted lines are the other fourth-point sheets, the numbers 55 in the other column of thumb-notches at the right the remainder of the second-point sheets.

The fifth-point sheets are about the same as the fourth-point sheets, except that the 60 thumb-notches, which appear at the bottom of the fourth-point sheets are entirely omitted. There are no added cut-out sections on the fifth-point sheets, as the classifications, or sub-divisions, thereon are final, although any point may

represent the final subdivision of topics, which depends on how minute a classification is desired.

The following is an example of how the system operates: Supposing I wanted to 70 look up what information I have or can obtain on the subject of "Records in connection with precision in closing a deal," I would refer to the uppermost sheet in the index, represented by the first diagram of Plate 75 Two, on which will be seen the names or subjects of Business, Chemistry, Music, etc. Of course, "Salesmanship" is a subdivision of "Business." By referring to the second diagram, which divides "Business" into various items, will be seen "Salesmanship." The item of "Salesmanship" is then subdivided, as per diagram No. 3, (the third-point classification,) on which may be found "Closing transactions," which is subdivided according to the fourth diagram, 80 on which may be found the topic "Precision." This topic is divided as per diagram No. 5, which contains the heading "Records." Therefore, the number of the folder 90 containing the information wanted is that which appears on the same line as the word "Records," or 12345. Other subjects are subdivided in a similar manner, the diagrams appearing on Plate Two showing a 95 complete subdivision of the subject "Business." It will be noted that the names, or topics, are written on the forms or sheets, which signifies that during the process of manufacture all lines are left blank, except 100 for the numbers, the user of the index supplying the names or subjects.

I claim:

1. A loose leaf binder comprising a back plate, posts secured to said back plate and 105 being adapted to carry sheets of paper, a casing slidably mounted upon said posts, thumb screws carried by said posts, and cam wedges interposed between portions of said thumb screws and the casing, and 110 adapted to move said casing down into clamping engagement with the paper.

2. A loose leaf binder comprising a back plate, posts secured to said back plate and 115 being adapted to carry sheets of paper, a casing slidably mounted on said posts, means associated with said posts for preventing upward movement of said casing with respect to said posts, and for moving said casing downwardly into clamping engagement with the paper.

3. A loose leaf binder comprising a back plate, sectional posts secured to said back plate and being adapted to carry sheets of 125 paper, a casing slidably mounted on said posts, means associated with said posts for preventing upward movement of said casing with respect to said posts, and for moving said casing downwardly into clamping engagement with the paper.

4. A loose leaf binder comprising a back plate, sectional posts secured to said back plate and being adapted to carry sheets of paper, a casing slidably disposed on said posts, thumb screws carried by said posts, said casing having cam teeth, and cam wedges carried by said casing, and rotatably mounted on said cam teeth, said wedges being adapted to engage portions of said thumb screws and to move said casing into frictional engagement with the paper when said wedges are rotated with respect to said cam teeth. 10

ALEX. G. SIEGERT.
